UNITED STATES PATENT OFFICE.

BRADLEY P. WHEELER, OF DULUTH, MINNESOTA.

WASTE-HEAT BOILER FOR REGENERATIVE FURNACES.

Application filed June 17, 1921. Serial No. 478,268.

This invention relates to improvements in regenerative furnaces, and more specifically to a removable slag pocket bottom combined with a waste heat boiler.

In furnaces of the regenerative type the flues which carry off the waste gases and also in turn serve to introduce the preheated gases or air, tend to become clogged with the finely divided matter carried by the gases and also with material fluxed from the walls of the passages by the intense heat. Those portions of these passages located under the end of the furnace are commonly formed with enlarged portions usually known as slag pockets. In furnaces using gases which are preheated, separate air and gas slag pockets are provided. These pockets serve in a measure to receive deposits of the finely divided matter or fluxed material, and it is necessary from time to time to stop the work of the furnace and clean out and in part rebuild these pockets. These particular points are constantly heated both when serving for the incoming and for the outgoing gases, and while their temperature toward the end of the incoming operation of the cycle may be somewhat lower than that when serving to carry off the outgoing gases, they are nevertheless always of comparatively high temperature. A certain amount of steam must be provided in connection with furnace operation for use in generating power or for other purposes. The slag pocket, due to its temperature forms a very satisfactory place for the interposition of a waste heat boiler. This pocket is considerably enlarged from the size of the adjacent uptakes and the passages leading to the checker chamber, and a boiler may be placed therein without seriously interfering with the draft of the furnace.

It is an object of the present invention to provide a removable bottom for furnace slag pockets or similar passages and to provide in association with such bottom a waste heat boiler.

It is a further object to provide a device of this character in which the bottom and boiler may readily be removed and replaced together.

Other and further objects will appear as the description proceeds.

Broadly, my invention comprises a truck adapted to be run in and out of a slag pocket or similar passage and when in place to serve as the bottom of the passage. It may also, in the preferable form, cover the lower por-

tion of the side walls of the passage. This truck carries upon it a boiler of any desired type, suitable connections for introducing water and permitting the passage of steam 60 being provided.

I have shown a preferred form of my invention somewhat diagrammatically in the accompanying drawings, in which—

Figure 1 is a fragmentary view showing a 65 cross section through a slag pocket with my device installed therein; and

Figure 2 is a view taken on line 2—2 of Figure 1.

In the drawings the furnace structure is 70 designated 3, this structure forming the uptake 4, and the slag pocket 5. The end of the slag pocket at 6 is connected with a flue (not shown) leading to the regenerative chambers. My removable truck 7 has its 75 bottom and sides 8 formed of metal and is lined with a layer 9 of fire brick or other refractory material. The truck is carried by wheels 10 upon track 11. Supported upon the truck is the boiler 12 which, as shown, is 80 of the water-tube type. The boiler is supported from the truck by supporting members indicated at 15 to 16. As shown in Figure 1, when the boiler and truck are in place in the slag pocket, the open spaces in the 85 end of the slag pocket are covered by a temporary wall 13 of refractory material. The upper portion 14 of the boiler may be connected to a steam main in any desired manner. This portion of the boiler is shown 90 supported by the bracket 17.

When installed as shown in the drawings, the truck 8 will receive the finely divided matter deposited by the gases and these gases will impinge against the tubes of the 95 boiler and heat the water therein. It is to be understood that when the boiler is in a slag pocket serving as the incoming end of the furnace, it is heated by the pre-heated gases, which may be gas or air, depending upon whether the device is inserted in the air or gas slag pocket. At the incoming end of the furnace these gases will come in through the end 6 of the furnace, pass through the slag pocket 5 and up through 105 the uptake 4. When this end of the furnace is serving as the outgoing end of the furnace the heated exhaust gases will come down the uptake 4, pass through the slag pocket and out through the end 6 thereof. Thus, regardless of the direction of operation of the furnace the slag pocket is constantly re- 110

ceiving gases at high temperature. When it is necessary to remove the boiler for cleaning the temporary wall 13 is broken away and the truck 8 is moved out upon its tracks 5 11. The boiler may then be removed from the truck if desired and the truck cleaned of any debris which it contains, and its lining of refractory material repaired or renewed as required. By providing a plurality of 10 trucks and boilers a clean boiler and truck may be installed immediately upon withdrawing the other truck and boiler and the wall 13 quickly replaced so that there need be no material delay in the operation of the 15 furnace.

By the combination of the truck and boiler a source of steam which takes its heat from one of the most satisfactory parts of the furnace for this purpose is secured, and this 20 boiler may be readily removed for cleaning when necessary. There is further secured a receptacle for the debris normally received in the slag pocket, and this receptacle is also removable, thus much decreasing the time 25 during which the furnace need be stopped for cleaning and removing the slag pocket bottom and walls.

I claim:

1. In combination with a passage of a regenerative furnace, a truck and a waste heat 30 boiler located in said passage, which passage is adapted for transmission of heated incoming and outgoing gases, said truck supporting said boiler and serving as a removable bottom for a portion of said passage.

2. In combination with a passage of a regenerative furnace, a truck and a waste heat 35

boiler located in said passage which passage is adapted for transmission of heated incoming and outgoing gases, said boiler being 40 carried upon the truck which is removably located in said passage, said truck covering the bottom and a portion of the sides of said passage and serving as a removable bottom for said passage.

45

3. In combination with a slag pocket of a regenerative furnace, a truck and a waste heat boiler located in said slag pocket, said boiler being carried upon the truck which is removably located in said slag pocket, 50 said truck being lined with refractory material and covering portions of the fixed sides and bottom of said slag pocket and serving as a removable bottom therefor.

4. In combination with a slag pocket of a regenerative furnace, a truck and a waste heat boiler located in said slag pocket, said boiler being carried upon the truck which is removably located in said slag pocket, 55 said truck being lined with refractory material and covering portions of the fixed sides and bottom of said slag pocket and serving as a removable bottom therefor, said boiler being removable from the truck.

5. Heat transmitting apparatus, comprising a truck having a closed bottom and a boiler supported thereon, said truck and boiler being adapted to be removably located in the passages of a regenerative furnace, the truck being adapted to serve as a removable bottom for said furnace passages.

Signed at Duluth, Minnesota, this 9th day of June, 1921.

BRADLEY P. WHEELER.
